UNITED STATES PATENT OFFICE.

CHARLES E. REDDIG, OF RICHMOND HILL, NEW YORK, ASSIGNOR TO WESTERN ELECTRIC COMPANY, INCORPORATED, OF NEW YORK, N. Y., A CORPORATION OF NEW YORK.

IRONING MACHINE.

Application filed October 18, 1921. Serial No. 508,515.

To all whom it may concern:

Be it known that I, CHARLES E. REDDIG, a citizen of the United States, residing at Kew Garden, Richmond Hill, in the county of 5 Queens, State of New York, have invented certain new and useful Improvements in Ironing Machines, of which the following is a full, clear, concise, and exact description.

This invention relates to ironing machines 10 and particularly to machines of the domestic type employed in households and small laundries.

It is an object of the invention to provide such machines with a feed table which is 15 simple and of sturdy construction, and which may readily and conveniently be converted to serve as a hand ironing board.

It is a further object of the invention to provide a feed table of the above character, 20 which also serves as a covering to protect the ironing roll and shoe from dust when not in use.

The invention provides a reversible feed table equipped on its under side with a padded surface for use in hand ironing. The table is swiveled in the center to a pair of supporting side brackets. For hand ironing the table is turned over so that the padded surface is on top, and is held in position by 30 two catches, one on each end. The supporting brackets are mounted on pivots offset from the plane of the table, so that when the machine is not in use, the whole table may be swung up over the ironing roll with 35 the padded surface underneath, protecting the ironing members, and hand-ironing surface from dust.

Other objects and advantages of the invention will appear from a consideration of 40 the following description taken in conjunction with the accompanying drawing and the appended claims.

In the drawing, Fig. 1 is a right end elevation of an ironing machine of the roll and 45 shoe type equipped with a feed table made in accordance with the present invention and showing the said table in full lines in position for hand ironing, and in dotted lines as a protecting cover for the ironing roll 50 and shoe; Fig. 2 is an end elevation showing the feed table in a serving position adjacent the roll, certain parts being broken away for the sake of clearness; Fig. 3 is a top plan view of the ironing machine, shown in Figs.

1 and 2, certain parts being shown in section 55 to permit illustration on a large scale; and Fig. 4 is a partial sectional view of the feed table and its supporting bracket.

Referring to the drawing, the ironing machine proper is preferably of the type disclosed in my copending application, Serial No. 402,848, filed August 11, 1920, the various parts of which are supported by frames 6 and 7 which are rigidly connected together by suitable cross bars, not shown in the 60 drawing. A main roll 8, which is covered with layers of fabric or felt, is secured to a shaft 9 mounted in the fixed bearings 10 and 11 in frames 6 and 7, respectively. Cooperating with the main roll 8 is a main ironing 65 shoe 12 of any well-known type suitably pivoted in the side frames. Mounted on the shaft 9, which projects beyond the outside of the frame 7, is an auxiliary roll 13 which may be covered with fabric or felt in the 70 same manner as main ironing roll 8. Cooperating with the roll 13 is an auxiliary ironing shoe 14, especially adapted for the ironing of small articles. The power for driving main and auxiliary ironing rolls 75 may be provided in any suitable manner as, for example, by an electric motor which may be bolted to the main frame of the machine and connected by belt or other means to suitable gear members enclosed in the journal 80 box 15. The means for yieldingly and removably holding the shoe 12 in cooperative engagement with the ironing roll 8, include pivotally mounted cams 16 extending from 85 which are arms 17 connected by a bar 18, 90 which may be grasped by the operator and by which the cams 16 may be moved in unison. At each side of the machine is a spring 19 which, together with suitable cooperating members, is adapted to hold the associated 95 roller 20 in engagement with different portions of the cam 16. The cams 16 are so formed, and the rollers 20 are so disposed in engagement with the cams that the cams allow the springs 19 to hold the shoe 12 in 100 yielding contact with the ironing roll 8, and also to hold the shoe to different distances out of engagement with the roll.

Pivotedly mounted on the inside of the tops of the frames 6 and 7 are the feed table 105 supporting arms or brackets 21 and 22. Swiveled in the arms 21 and 22 at points 23 is the feed table 24. One side of the feed

table 24 has a flat, smooth surface 25, adapted to act as a guide member from which articles are fed to the ironing roll 8, as is more clearly shown in Fig. 2. The opposite side 5 of the feed table is provided with a thickly padded surface 26, suitably held to the board as by means of tacks, and forming an auxiliary hand ironing surface. The right and left ends of the table 24 are each provided 10 with a pair of recesses 27 and 28, positioned at the same distance on either side of the swivel 23 so that they are adapted selectively to register with the single recess 29 in the arms 21 and 22, respectively. Thus, 15 when the auxiliary ironing surface 26 is in the operating position shown in Fig. 1, the recess 27 in the table will register with the bracket recess 29; and when the smooth surface 25 is moved to the feeding position 20 shown in Fig. 2, the table recess 28 will register with the bracket recess 29. A pair of removable pins or dowels 30 are provided, one for each end of the table, and are adapted for insertion in either recesses 27 or 28 25 and the bracket recess 29 to lock the table in either the ironing or the feeding position. The pins 30 are readily removable and are provided with bent-over portions 31 forming handles, but any other suitable locking 30 means may be employed.

Owing to the pivotal support of the combination feed table and the fact that its length is less than the space between the arms 17, the table may be moved to a covering 35 position over the roll 8 and shoe 12, as shown in dotted lines in Fig. 1. When in this position the table protects the roll and shoe as well as the padded surface 26 from dust. In order that the combination feed 40 and ironing table may be made of a convenient width and still be swung under the shoe-actuating bar 18, the arms or brackets 21 and 22 are bent, as shown in the drawings, so that they may be mounted on the pivot 32, 45 which is offset from the plane of the table. By so arranging the pivot it is possible not only to swing the combination feed and ironing table under the actuating bar 18 while still retaining the arms 17 of the bar of 50 convenient short length, but also to swing the table through a wide angle to a position where it completely covers and protects the

ironing roll and padded surface 26 from dust.

Hinged to the main frames 6 and 7 is a 55 delivery board 33, which is movably held by any suitable means in either of the positions shown in Figs. 1 and 2. This board may also be dropped to a vertical position if desired. 60

What is claimed is:

1. In an ironing machine, a table provided with one surface adapted to serve as a feed table for the ironing machine and another surface adapted to serve as a hand ironing board, adjustable brackets for supporting said table and means whereby either surface of said table may be brought into operative position in the same position of the brackets. 70

2. In a power operated ironing machine, a table provided with one surface adapted to serve as a feed table for the ironing machine and another surface adapted to serve as a hand ironing board, and brackets for supporting said table said table being pivotally mounted in said brackets whereby either surface may be brought into operative position without movement of the brackets. 75

3. In a power operated ironing machine 80 having cooperating ironing members, a supporting frame in which said ironing members are supported, a pair of supporting side brackets pivoted in said frame, a feed board swiveled on said supporting brackets, a padded surface suitable for hand ironing disposed on one side of said feed table, and means for selectively locking said table in a feeding and ironing position. 85

4. In a power operated ironing machine, 90 cooperating ironing members, a supporting frame for said ironing members, adjustable brackets mounted upon said frame, and a reversible table carried by said brackets adapted in one position of the brackets to be 95 used either as a feed table or hand ironing board and in another position of said brackets to serve as a protective covering for the cooperating ironing members.

In witness whereof, I hereunto subscribe 100 my name this 13th day of October A. D., 1921.

CHARLES E. REDDIG.
